ELECTRICAL INDICATING MEANS

Merton L. Haselton, New York, N. Y., assignor, by
mesne assignments, to The Teleregister Corpora-
tion, New York, N. Y., a corporation of Dela-
ware

Application October 6, 1928, Serial No. 310,719

27 Claims. (Cl. 177—353)

This invention relates to electrical indicating means and more particularly to indicating or signaling apparatus and methods, according to which indicating devices corresponding to a large number of different items may be operated at various receiving stations and all controlled over a single wire or a small number of wires from a central point or points.

While not limited thereto, the invention is particularly adaptable to the transmission and posting of varying quotations or prices of a multitude of items such as stocks, bonds or commodities.

The transmission of the quotations may be controlled from central points such as stock exchanges, and arrangements are provided whereby a large number of brokers or others may be simultaneously provided with quotation service for as many of the stocks or other items as are of particular interest at each receiving station.

The objects of this invention include the provision of apparatus of the above indicated class which will be rapid, accurate and dependable in operation, and if desired, operable over a single line wire.

Further and more specific objects, features and advantages will more clearly appear from the following description, when taken in connection with the accompanying drawings and the appended claims.

The invention consists in the novel signaling features, circuit arrangements, methods and combinations of circuits and parts as hereinafter described by way of example only, as being illustrative of a certain preferred embodiment of the invention.

In the drawings, Fig. 1 comprises a schematic diagram showing in part the circuit arrangements of a receiving equipment comprising one embodiment of the invention. It will be noted that this figure is divided into parts 1a, 1b, 1c and 1d, and the figure extends over four sheets;

Fig. 2 is a schematic diagram illustrating the general method of transmission utilized in connection with this invention;

Fig. 3 illustrates in further detail a portion of the schematic diagram of Fig. 1, which is repeated several times in the circuit arrangements, as indicated particularly in Fig. 1b;

Fig. 4 comprises a tabulation of the circuits and relays of Fig. 3 and indicates the manner of operation of the same;

Figs. 5 and 6 respectively illustrate in further detail portions of the schematic diagram of Fig. 1b, and

Fig. 7 is a sectional view of one type of indi-

cator that may be used in the system disclosed.

According to the embodiment of the invention here shown, circuit arrangements are provided for operating a multitude of rotatable electro-magnetic digit indicators comprised in a broker's board such as disclosed in my co-pending application Serial No. 276,883, filed May 11, 1928, now Patents Nos. 2,067,187 and 2,117,661. The broker's board as described in that application embodies indicators for individually posting each of the four digits of each quotation, such as "open," "high," "low" or "last" of each stock or other item. The circuit arrangements herein-after described in addition provide for posting the "yesterday's close" or other like quotation, controllable in certain respects independently of the "open," "high," "low" and "last" quotations or their equivalents. The indicators of the present apparatus like those of my co-pending application, are arranged to be operated step-by-step by the use of spaced impulses. Such indicators are also designed to be restored to a normal setting prior to the setting up of a new quotation, and such restoration is preferably accomplished by applying a total of at least ten impulses to all of the indicators which are to be reset. These ten restoration impulses serve to advance each of the indicators individually until they arrive at a predetermined normal position, whereupon a control switch at each indicator is operated to render any further restoration impulses ineffective to operate the indicator thus restored. Accordingly, the provision of at least ten restoration impulses insures movement of all of the indicators which are to be reset, to their normal positions, regardless of their previous settings and regardless of whether the previous settings were accurate or otherwise. The details of construction of the indicators and the broker's board per se are set forth in full and claimed in my aforesaid patents, and accordingly the same will not be here described in further detail. In this connection, reference may be made to Fig. 1d, however, which illustrates the electrical connections for a typical group of such indicators for posting the digits of the quotations for one stock.

The circuit arrangements of Figs. 1 and 2 will now be briefly outlined to give the general scheme of operation of the system and thereafter the various circuits will be described in further detail.

It will be understood that numerous brokers' boards located at separated points may be controlled from a single transmitting device. A

transmitting device adapted to the particular receiving circuits hereinafter described is schematically indicated in a general way at the left-hand side of Fig. 2. The system of multiplex transmission embodying the use of a well known type of synchronous distributor is used. In Fig. 2 a distributor is indicated at 10 adapted for use with a five unit code system. Five transmitting keys are schematically indicated as at 11 for applying current from the source 12 to the desired segments 13 on the distributor to transmit impulses according to a predetermined code relationship over a line wire 14. It will be understood that the transmitting keys 11 may be operated automatically or semi-automatically by suitable transmitting apparatus forming no part of the present invention.

The line wire 14 may be branched as indicated at 15 to run to the various receiving stations. Line relays as at 16 may be located at each receiving station, a ground return from each of such relays being provided as indicated to complete the line circuit back to the source of current 12. A typical receiving station distributor is schematically indicated at 17 and its rotating arm 18 may be impulsively energized from a source of current 19 and connection wire 19' whenever the relay 16 is actuated, and the impulses thus received will be distributed according to their predetermined time relationship to the five receiving selector relays such as schematically indicated at 20.

It will be understood that the rotating arms of the transmitting and receiving station distributors above described will be maintained in synchronism by arrangements well known in the art of multiplex telegraphy. For example the so-called "stop-start" distributor system may be used. Inasmuch as such distributors are well known, the details of construction and operation thereof will not be described herein except in so far as necessary to reveal the manner in which the same may be utilized to operate the receiving station circuits hereinafter described.

In Fig. 1a a well known form of "stop-start" distributor is indicated at 21. This distributor is arranged to distribute impulses received over the line 14 to the five receiving selector relays 22 which function to prolong the effective length of the line impulses to insure proper operation of the circuits. The relays 22 also function to delay actual operation of the succeeding circuits until the distributor has completed one revolution, thus insuring proper functioning of the apparatus in accordance with the intended code.

From the relays 22 the coded impulses are brought into either a group of bus wires 23 for operating the selector circuits shown in Fig. 1, or if such circuits already have just previously been operated, a multicontact relay 24 will have shifted the circuits to impart the coded impulses to bus wires 25 running to substantially a duplicate selector apparatus, whereby such duplicate apparatus may be used to select another stock while the indicators for the stock chosen by the circuits shown in Fig. 1 are being reset.

During the initial revolution of the distributor at 21 a group of coded impulses will be received, which at the termination of the first revolution of the distributor are imparted to the busses 23 and thence through busses 26 into a group of "code register relays" located at 27 in Fig. 1b and shown in further detail in Fig. 3. These relays will function to place a grounded battery connection upon one of the bus wires 28,

which in turn will complete a circuit through one of the relays 29, 30, 31, 32, 33, 34, 35, 36 or 37 (see Fig. 1c). The operation of one of the relays 29 to 33 will determine whether or not the "open," "high," "low," "last" or "yesterday's closing" quotation is to be reset for whatever stock is subsequently selected. The operation of the relay 34 will cause the "high" and "last" indicators to be operated together. The operation of relay 35 will cause the indicators for the "low" and "last" to be operated together, and if relay 36 is energized, then the "open," "high," "low" and "last" will be operated in "unison." If the relay 37 is operated, the existing "open," "high," "low" and "last" quotations posted for the particular stock to be chosen will be "wiped out" or in other words, the indicators therefor will be restored to exhibit blank spaces.

Therefore, the first group of coded impulses resulting from the initial rotation of the distributor at 21 will choose or select for operation one of the relays 29 to 37 and thus determine in which of their various different characteristics the quotations to be subsequently selected will be changed.

Upon arrival over the line wire of the second series of coded impulses, the distributor at 21 will be released for another rotation and a second group of coded impulses will be prolonged at the relays 22 and subsequently simultaneously applied to the busses 23. However, due to the operation of certain relays hereinafter described in connection with Fig. 3, this second series of impulses will be conducted over connection wires 38 into a group of code register relays at 39, which as above stated are also arranged as shown in detail in Fig. 3. The operation of the code register relays 39 in turn cause a grounded battery connection to be applied to a selected one of the connection wires 40, which operation in turn causes the energization of one of the relays as at 41, 41a, 41b, etc. In a similar manner, the third group of coded impulses received during the third rotation of the distributor are applied to connection wires 42, and thence to a third group of code register relays at 43 for choosing one of the wires 44. This selection of one of the wires 44 in turn results in the energization of one of the contacts as at 45, 45a, 45b, etc., a group of each of which is provided respectively upon the relays 41, 41a, etc.

Also, in a similar manner, the fourth group of coded impulses may be conducted over connection wires 46 to a fourth group of code register relays 47, which in turn cause a grounded battery connection to be applied to a selected one of the wires 48'. The wires 48' in turn are continued by suitable conductors as at 48' (see Fig. 1c) which conductors form the horizontal bars 60 of a selector grid, the vertical conductors or bars of which, as at 49 respectively being electrically connected to the various relay contacts 45, 45a, 45b, etc., whenever the corresponding relays 41, 41a, etc., are energized.

The three groups of code register relays 39, 43 and 47 therefore function to choose a desired stock or other item, the quotations for which are to be reset. Such choice of a particular stock involves applying a grounded battery connection to one of the horizontal grid conductors 48 and to one of the vertical grid conductors 49. Relatively demountable connections or quick-detachable plugs may be applied as at 50, 51 and 52 at the various intersection points of the horizontal and vertical grid conductors. From these

detachable or plug connections pairs of relatively flexible selector circuit wires as at 53 may extend for operating certain relays on the brokers' boards as hereinafter explained. That is, if there is a detachable or plug connection applied at the intersection of the particular horizontal and vertical grid conductors which have been chosen by the above described operations, then the selector circuit wires leading from such connection or plug will be energized for causing the corresponding indicators on the broker's board to be energized. It will be understood that an intersection of a horizontal and vertical conductor is provided on the grid board for each of the various stocks or other items for which service is made available by the system. However, individual brokers will not be interested in many of these stocks or items, so that in many actual installations, selector circuits and detachable connections or plugs may be applied to only those intersections on the grid board corresponding to stocks of particular interest at such installations.

The fourth revolution of the distributor at 21 will be immediately followed by a fifth revolution, which in turn will impart a group of coded impulses from bus wires 23 to connection wires at 54 for operating a fifth group of code register relays at 55, the arrangement of which is also shown in detail in Fig. 3. The code register relays at 55 will cause a ground connection to be applied to one of the connection wires at 56 running to a local impulse transmitter or counting device 57 which is illustrated in detail in Fig. 6. In like manner, the sixth, seventh and eighth revolutions of the distributor at 21 will cause groups of impulses to be imparted to connection wires 58, 59 and 60 respectively for operating code register relay groups at 61, 62 and 63 respectively. The code register relays 61, 62 and 63 when thus operated, cause a ground connection to be placed upon one of the wires of each of the groups 64, 65 and 66 respectively, all of which wires run to the local impulse counter 57 for controlling the operation of the same at the proper time.

Meanwhile, however, at the completion of the selecting operations by the code register relays 47, one of the relays embodied in the group 47 not only serves to transfer the succeeding group of code impulses to the code register relays 55, but also initiates the operation of a local impulse counter or transmitter 67, the details of which are illustrated in Fig. 5. The operation of the impulse counter 67 is started through the medium of a connection wire 68 running from the code register relays 47.

The purpose of the impulse counter 67 is to apply a series of ten impulses to each of four bus wires at 69 and after this is accomplished, a relay associated with this impulse counter and operating over connection wires 70 and 70', causes the impulse counter 57 to be set in operation for applying a predetermined number of impulses to each of the bus wires 71, 72, 73 and 74 which are joined respectively to the several bus wires 69. The last four groups of coded impulses, which as above explained cause ground connections to be applied to one of each of the groups of wires 56, 64, 65 and 66, serve to determine the values respectively of the four digits representing the new quotation which is to be posted by the selected indicators. The ten impulses initiated on each of the bus wires 69 by the impulse counter 67 will serve to insure

the advance of the indicators for each of the four digits of the stock selected, through a sufficient number of steps to restore the same to a normal or "blank" setting. Thereafter the impulse counter 57 as controlled by the four grounded connections 56, 64, 65 and 66, will serve to apply to the bus wires 71 to 74 respectively in each case, a number of impulses corresponding to each of the four new digits to be posted by the indicators. That is, the code register relays 63, 62, 61 and 55 respectively correspond to the hundreds, tens, units and fractions digits to be posted. Likewise, the bus bars 71, 72, 73 and 74 correspond respectively to the hundreds, tens, units and fractions digit indicators.

The keys 11 of the transmitter shown in Fig. 2 cause signals to be impressed on the segments 13 of the distributor 10 in various combinations to transmit coded impulses representing digits and to transmit coded impulses representing the blank position, and the various relays 22 of Fig. 1a are set up in combinations in accordance with the code transmitted, whether such code represents digit control or blank control. One advantage of the arrangement is that if there is a price change, for example, from ten to nine, then a digit will be transmitted to reset the units indicator to 9, and a blank will be transmitted to set the tens indicator drum to blank position. Thus the transmitter is arranged to transmit item selection signals and signals corresponding to a variable number of digits and to exercise an additional control dependent upon the number of digits transmitted.

Meanwhile during the operation of the local impulse counters 67 and 57, succeeding groups of code impulses from the distributor will be imparted over the bus wires 25 as above referred to (see Fig. 1a), to a duplicate selector apparatus (not shown in the drawings) for the purpose of choosing another stock for which the indicators are to be reset, and for the purpose of storing in other code register relays, impulses which will determine the resetting of such other selected indicators.

In this way the part of the receiving circuit shown in Fig. 1 may be utilized during the actual operation of the chosen indicators to reset the same, while in the other half of the system the necessary impulses are being stored up for later changing another quotation. The two portions of the receiving apparatus may thus be alternately brought under the control of the distributor.

In each of the two portions of the receiving apparatus, as soon as the local impulse counter 57 has completed its operation of supplying the desired impulses, it automatically performs the additional function of releasing the setting of all of the code register relay groups, whereby the same are restored to normal condition ready for the next cycle of operations.

Referring to Figs. 1c and 1d, it will be observed that a plurality of busses 75, 76, 77, 78 and 79 extend from the contacts of relays 29 to 33 respectively. These busses are continued into the broker's board per se and run adjacent to the indicators for all of the various stocks or other items. A plurality of similar busses 80, 81, 82, 83 and 84 are also indicated and these are intended to cooperate with the duplicate selector apparatus above referred to in the same manner that the busses 75 to 79 cooperate with the selector equipment above described. As will be herein-after further explained in detail, either of these two sets of busses may be alternatively associated

with the indicators for any particular stock. A multicontact relay as at 85 is provided for the connections to the indicators of each stock, whereby when such relay is actuated, the indicators for the particular stock chosen will be connected in circuit with one of these groups of busses. The multicontact relays as at 85 in turn are operated over selector wires as at 86, which as indicated in Fig. 1c are associated with the selector circuits as at 53, through relays as at 87.

The connections associated with one of the selector circuits 53 may be conveniently explained in detail at this point. It will be recalled that the code register relay group 43 serves to choose one of the connection wires 44 and to place a grounded battery connection thereon. Let us assume that such a battery connection has been applied to the connection wire indicated as 44' in Fig. 1c. Let us also assume that relay 41d has been selected and energized by the operation of the code register relays 39. Then the connection wire 44' will run from the grounded battery connection at the code register relays, through the corresponding contact of relay 41d, to one of the vertical conductors indicated at 88 on the grid board, and such conductor will therefore be connected to the battery. Let us further assume that one of the horizontal grid conductors as indicated at 89 has likewise been connected to a grounded battery by the operation of code register relays 47. The detachable plug or connection shown at 52 is provided with two contacts electrically connected respectively to the intersecting conductors 88 and 89 so that the battery circuits thereof are continued respectively through the selector wires 53. It will be observed that the circuit of the conductor 88 runs through the relay 87 and thence to a ground return. Hence, this relay will be energized closing its contact 90, which completes the battery circuit of conductor 89 through wire 86 to relay 95 and thence to ground return. Therefore, the energization of the intersecting conductors 88, 89, on the grid board as a result of the selecting operation, results in the operation of the multicontact relay 85 corresponding to the particular stock selected.

Operation of distributor.—Reverting now to the description of the distributor 21, the arrangement and operation of the same will be described in detail.

The distributor is provided with a rotatable arm 91 operated by a rotating shaft 92 through a friction clutch 93, which in turn may be connected to a constantly driven shaft member 94. The shaft member 94 may be driven as by a motor 95 at a speed slightly greater than the maximum normal rotational speed of the shaft 92 and arm 91. A locking and releasing member is indicated at 96, the position of the same being magnetically controlled by relay or solenoid 97, so that when the latter is deenergized, the locking member 96 will engage the rotating arm 91 and prevent rotation of the same. When the solenoid 97 is energized, the same will retract the locking member 96 and permit the rotatable arm 91 to rotate through one revolution in the direction indicated by the arrow.

An impulse generating device is indicated at 98, the same being operated from the shaft 94 to apply impulses from a grounded source of current 99 to a bus wire 100 for actuating the indicators step-by-step through circuits herein-after described. Gear boxes as at 101 and 102

are preferably interposed in the shaft 94 at each side of the impulse generating device 98, whereby the impulse generator may be arranged to generate impulses at a desired predetermined rate in respect to the rate of rotation of the distributor arm 91. That is, such gear boxes may be so designed as to operate the distributor at the proper speed to economically utilize the elapsed time necessary for the actual operation of the broker's board indicators.

It will be observed that the distributor 21 has an outer ring comprised of five code segments 103 to 107 inclusive, which are respectively connected to the circuits of the five receiving selector relays 22. This outer ring of the distributor also has a sixth insulated segment 108 connected to a contact 109 of a starting and holding relay 110. The circuit from segment 108 through contacts 109 is continued through an associated starting and holding relay 111, and thence through a ground return to a battery 112, which in turn is connected to a segment 113 on another ring of the sunflower. Whenever the rotating arm 91 passes over segments 108 and 113, these two segments are connected together by way of a connection on the arm as indicated at 114. The major part of the ring in which segment 113 is located comprises a segment 115 also associated with the code segments 103 to 107 by means of the connection 114. The distributor has in addition two inner rings having cooperating segments 116 and 117, which during a portion of each revolution of the distributor are connected together by a connection 118 carried by the rotatable distributor arm.

The operation of the distributor is as follows: When the line wire 14 is deenergized, line relay 16 will be deenergized and its two sets of contacts 119 and 120 will be open. Assuming that the distributor arm is in locked position, when an impulse arrives over the line 14, the relay 16 will close its contacts 119 and 120, thus applying current from a grounded source 121 to the segments 115 and 116. From segment 116 the circuit will be continued through connection 118, segment 117 to relay or solenoid 97, and a ground return, whereupon this relay or solenoid will unlock the catch 96 and permit the rotatable arm to start a revolution. As soon as the rotatable arm reaches segment 115, it will be in a position to impart any succeeding impulses arriving over the line wire to the several code segments 103 to 107 by way of the connection 114. Therefore whenever the rotatable arm arrives over a code segment at a time when an impulse is arriving over the line wire, circuits will be established as follows: grounded source of current 121, contact 120, segment 115, one of the segments 103 and 107, through one of the relays 22, connection wire 122 to release contact 123 under the control of the relay or solenoid 97. Contact 123 will be closed at these times because solenoid 97 will be deenergized as soon as the rotatable arm leaves segment 117.

Operation of selector relays 22.—Let us assume that for example two of the relays 22 have become momentarily energized in the manner above described. Such two relays will immediately be provided with momentary holding circuits by way of contacts as at 124, which will complete such holding circuits through the winding of relay 110 to a battery and ground at 125 and through the ground return, contact 123 and connection 122. Relay 110 when thus energized will close the contacts 109 and prepare a circuit therethrough.

After a very short interval, the rotatable distributor arm will arrive at the sixth segment 108, which will result in the closing of a circuit through contacts 109 and relay 111. Contacts 126 and 127 of this relay will thereupon be closed for a short interval, whereupon circuits will be completed from a ground at 128, through contact 127, through contacts as at 129 of such of the relays 22 as have been energized, thence through the corresponding connections 130 and through the contacts of the multicontact relay 24 to the busses 23 or 25 as above explained. Meanwhile another circuit is established from grounded battery 131, through contact 126, thence through break contact 132 on relay 24, and through the winding of a relay 133. The relay 133 thereupon picks up and establishes a holding circuit for itself through its contacts 134 from a grounded battery 135, the circuit being continued through a "release bus" 136 which is normally grounded within the local impulse transmitter 57 in a manner hereinafter explained. This bus remains thus grounded and the relay 133 remains energized until the new quotation is posted or other actuating operations completed, and until such time as the code register relays are to be released in the manner above outlined. Meanwhile relay 133 maintains its contacts at 137 and 138 closed, the former providing a "battery supply" circuit from a grounded battery connection at 139 to a "battery supply" wire 140. The contact 138 applies a ground as indicated, to a "ground supply" wire 141. These "battery supply" and "ground supply" wires are instrumental in the control of the code register relay groups as hereinafter explained and hence these circuits are maintained by the relay 133 and its holding circuit until the impulse counter 57 completes the actuation of the chosen indicators.

The original circuit of relay 133, however, and contact 126 will be opened as soon as the distributor arm passes segment 108 and completes its revolution, since at this time battery 112 will become disconnected, permitting relay 111 to "drop out." The interval during which the relay 111 is maintained energized thus determines the duration of the elongated code impulses which occur in the busses 23 and 25.

Also, when the distributor arm arrives again at its starting position, it will be at least momentarily stopped by the catch 96 and it will wait at this position until another "starting impulse" arrives over the line wire for energizing solenoid 97. This next starting impulse will of course open contact 123 and thus release the holding circuits of relays 22 and also release relay 110, thereby restoring the distributor circuits to condition for receiving another group of coded impulses.

Operation of duplicate selector apparatus.—As soon as the code register relays 63 have completed their operations, they will apply in a manner hereinafter described, a ground connection to a wire 142 (see Fig. 1b), and thereby complete a circuit through relay 24 and its operating battery and ground at 143. Relay 24 will thereupon operate its two-way contacts as at 144 and shift the same so as to connect the several wires 130 to the busses 25 running to the duplicate selector apparatus, whereby the coded impulses resulting from the succeeding rotation of the distributor will be delivered to such duplicate apparatus while the part of the system shown in Fig. 1b is completing its operation. Relay 24 thereupon immediately establishes a holding circuit for itself through its contact 145 and a contact 146

provided on a relay 147. Also relay 24 moves its contact 132 to the "make" position whereby a relay in the duplicate apparatus corresponding to relay 133 may be operated.

5 After the appropriate group of coded impulses are delivered to the duplicate apparatus, such apparatus will automatically apply a current to relay 147 in substantially the same manner that relay 24 was operated, whereupon the holding circuit of relay 24 will be released because of the opening of contact 146. The circuits will now be in condition for discharging a group of coded impulses into the busses 23 again.

15 *Operation of code register relays.*—The circuits of the code register relays as shown in Fig. 3 in connection with the table of Fig. 4, as above stated, are repeated eight times in the circuits as shown in Fig. 1b and accordingly the following description is made applicable to such relays as interposed in each of these eight positions.

20 The respective relays of this group are designated by the letters (A) to (G) inclusive. Five connection wires leading out to the busses 23 are designated respectively as K1 to K5 inclusive. 25 The connection leading out to the "battery supply" wire 140 (as with code register relays 27, 39, 43 and 47) or alternatively, to the "ground supply" wire 141 (as with code register relays 55, 61, 62 and 63) is identified in Fig. 3 by the letters "GS or BS". In addition, each group of code register relays has an incoming grounded wire or "ground in," "GI," and an outgoing ground wire, or "ground out," "GO," the relationships of which are indicated in Fig. 1b.

30 Assuming that with code register relays 27, for example, a ground has been applied to "GI" by the operation of relay 133, then such ground will be extended through contact 148 of relay A, to relay B, which will be energized by its battery 149, through the ground return indicated. Relay B has five contacts as at 159 for completing the circuits of wires K1 to K5 respectively, through relays C to G inclusive respectively, by way of battery and ground connections as at 151. 45 Below each of the relays C to G inclusive, are a plurality of interconnected "make" and "break" contacts under the control of these relays and all arranged to be connected either directly or indirectly to "GS" or "BS" when the relays are actuated in proper combinations. These contacts are also all interconnected directly or indirectly with one or more of the outgoing 11 wires, as at 152. These 11 wires (numbered respectively 1 to 11 with small numbers) represent the groups 50 of wires 28, 40, 44, 48', 56, 64, 65 or 66. It will be noted that 11 wires are provided in each of the last four groups, whereas in the first four groups only ten need be provided. However, if desired, the eleventh wire may be provided in all groups 55 whereby a "spare" will be available for future purposes in connection with the first four groups if desired. It will be understood that coded impulses will arrive, for example over one or two of the wires K1 to K5, and the manner in which 60 these impulses serve to actuate the relays C to G in the proper combinations to choose one of the outgoing wires 152 is indicated by the table in Fig. 4. For example, if "K leads" 1 and 2 are energized by impulses, the first outgoing lead will 65 be attached to "GS or BS" by reason of the operation of relays C and D. The circuits which accomplish this may be readily traced on Fig. 3 without further explanation.

70 The coded impulses, however, will persist only 75 for a short interval, whereas it is desired to main-

tain the "GS or BS" connection to the chosen outgoing lead 152 for a longer period of time. Therefore each of the relays C to G, is provided with a holding circuit running from GI, through coil of relay A, to the top relay contacts as at 153, thence through one or more of the relays C to G, to battery and ground. So long as the impulses persist over wires K1 to K5, relay A will not be energized by this circuit, since contacts 153 will be grounded through wires K1 to K5. However, when the K1 to K5 impulse circuits are broken by the removal of the ground connection at 128 (see Fig. 1a), then relay A in series with one or two of relays C to G inclusive will be energized by batteries as at 151. The relay A as thus energized, closes its contact at 154 for applying and maintaining a ground connection to "GO." With each set of code register relays it will be noted that "GO" runs to the succeeding set of code register relays, (to wire 142 in the case of register relays 63) whereby the next revolution of the distributor may impart its group of coded impulses to the succeeding set of code register relays. Meanwhile, however, relay A upon becoming energized, opens its contact 148 and thus releases relay B so that no more than one group of coded impulses may pass into each set of register relays.

Operation of impulse counters.—When code register relays 47 complete their operation and apply a ground to the "GO" connection, such ground as above explained, not only prepares the code register relays 55 for operation, but also provides a "GI" connection to the impulse counting device 67 by way of connection 68. This will start the operation of the impulse counter 67 for providing ten impulses to insure restoration to normal of all of the indicators which have just previously been selected. When the impulse counter 67 completes its operation, it functions to apply a ground connection to its "GO," which ground connection is continued to "GI" of impulse counter 57 by way of connection wire 70.

Impulse counter 57 will be first described, inasmuch as the operation of impulse counter 67 will thereafter be obvious in view of the similarity of the circuits.

"Actuation" impulse counter.—Referring to Fig. 6, it will be recalled that these circuits operate to impart a predetermined number of impulses to each of the four wires 71 to 74 for actuating respectively the hundreds, tens, units and fractions digit indicators. Also, in each of the groups of 11 wires, 56, 64, 65 and 66, under the control of the code register relays, one wire has been grounded for determining the particular digit to be posted for each decimal place. The operation of the impulse counter begins as above stated when a ground is placed on its "GI" and immediately after the completion of the "restoration" of the chosen indicators. Impulse carrying wires 100 and 100a are indicated at the lower part of Fig. 6 and both of the same carry impulses from the impulse generator 98 above referred to. The wire 136 at the bottom of the figure, it will be recalled, comprises the wire which provides a holding circuit for relay 133, this wire being normally grounded through a relay contact 154, this ground not being removed until after this impulse transmitter has imparted the required number of impulses to reset the indicators.

The ground "GI" completes a circuit from the impulse wire 100, through a stepping magnet 155, in a manner obvious in Fig. 6. The stepping

magnet 155, as will be understood from the conventional showing of the drawing, is mechanically connected to a group of rotary switches 156, 157, 158, 159 and 160, so as to advance the stepping impulses supplied over connection 100. "GI" also energizes a relay 161, the circuit being completed through battery and ground at 162, but this relay being slow operating, does not pull up until the rotary switches 156 to 160 have been "stepped" from their rest position shown. "GI" is also connected to bottom contact springs 163, 164, 165 and 166, which are operated respectively by relays 167, 168, 169 and 170, the circuits through said bottom springs then continuing on through the winding of a relay 171 to battery and ground. Accordingly relay 171 is at once operated so that it opens its contact at 172, which contact controls the circuit of a relay 173 and prevents relay 173 from operating until all four of the relays 167 to 170 have pulled up and opened their bottom contacts 163 and 166.

The rotary switch 156 having stepped one step, grounds its wiper, inasmuch as all of its contacts 174 except the first, are grounded as indicated. This completes a circuit from these grounded contacts through the windings of relays 175 and 176 to battery and ground at 177, thus actuating these relays. The relay 175 in actuating, closes its contacts 178, thus replacing a ground on the stepping magnet 155, the "GI" ground having been just previously removed by the delayed operation of relay 161 controlling a contact 179. Relay 176 in actuating, closes its contacts 180, 181, 182 and 183, which connects the impulse wire 100a to the four upper contact springs 184, 185, 186 and 187 respectively of the relays 170, 167, 168 and 169. From these upper contacts, impulses may thus be imparted respectively to the four outgoing bus wires 74, 71, 72 and 73. Relay 176 also closes its lowermost contact at 188, placing a ground in position to hold up any of the relays 167, to 170, through their contact springs 189 to 192 respectively.

With each impulse arriving over the impulse wire 100, the stepping magnet 155 will be operated, thus advancing step-by-step the wipers on the switch banks 157 to 160. Eventually, however, each of these wipers will arrive at a contact which has been grounded by the action of the impulse storage relays 55, 61, 62 and 63 as above explained, such grounded contacts corresponding respectively to the digits of the quotation to be set up. Assuming that the third point designated as 193 on the switch 157 has been grounded, as the wiper for this switch comes to such point, a circuit is completed from this ground connection through the wiper and connection wire 194, thence through winding of relay 167 to battery and ground. Relay 167 in pulling up, opens its top contact 185, cutting off impulses to outgoing bus 71, but without interfering with the further application of impulse wire 100a to the other busses providing the relays 168, 169 and 170 have not yet been actuated. Relay 167 in actuating also places a holding ground on its own winding through its contact 189 and the contact 188 as above explained. Relay 167 also closes a bottom "make" spring contact 195 which in part prepares a grounded circuit which will eventually operate relay 173.

Each of the rotary switches 158, 159 and 160 in conjunction with their relays 168, 169 and 170 operates in a manner similar to the operation of switch 157 and as the last of these relays

operates, all of the contacts 163, 164, 165 and 166 will become opened, thus releasing relay 171 and permitting its contact 172 to close. At the same time all of the bottom "make" spring contacts 195 of the relays 167 to 170 will have become closed, thus completing a ground connection running from 196, through the four bottom "make" spring switches as at 195, and through contacts 172 to relay 173 to battery and ground.

Relay 173 thereupon opens its "break" contact at 197 and thus removes impulse wire 100 from the stepping magnet 155. However, contacts 197 in moving to their "make" position, apply a "buzzer" contact circuit to the stepping magnet through contacts 198. The stepping magnet is thereupon provided with impulses in rapid succession through the "buzzer" contact from the battery and ground 199 and accordingly the rotary switches will be quickly advanced to normal position, at which the ground will be disconnected from the wiper 156 for stopping the operation of the stepping magnet and for releasing relays 175 and 176, the latter in turn releasing the holding circuits of relays 167 to 170. Relay 173 will then become released and relay 171 may then be again energized for a short interval.

The operation of relay 173, in opening its contact 154, opens the release bus circuit 136, which in turn permits relay 133 to drop out for removing the "battery supply" and "ground supply" to the several groups of impulse storage relays, which in turn also results in the removal of the ground connections to "GI" in each of the impulse counters at 57 and 67. With this ground removal, relay 161 drops out, as does also relay 171, completing the restoration of the circuits to normal condition.

"Restoration" impulse counter.—The operation of the impulse counter of Fig. 5 for delivering the ten indicator restoration impulses will be readily understood from the above description. Corresponding parts have been identified by the same numerals accompanied by prime marks. However, it will be noted that as this impulse counter always provides ten impulses over the busses 69, only one control switch as at 157' is required. The tenth point as indicated at 200 is permanently grounded on this control switch, so that it will be permitted to always control the transmission of ten impulses whenever it is operated. Of course in lieu of the four controlling relays 167 to 170, a single controlling relay as at 167' may be provided. Also, a contact 154' on relay 173' is arranged to "make" instead of "break" when this relay is energized. This is for the reason that with this impulse counter, it is desired to have the same perform the final operation of imparting a grounded connection to "GO" for initiating the operation of impulse counter 57. Also, in order that the relay 173' after once being energized, may be kept pulled up as long as a ground connection is continued on "GI," an additional contact 201 is provided on relay 173', whereby when this relay is actuated, a holding circuit is provided as indicated on the drawings from "GI," through the coil of relay 173', to battery and ground. This relay is thus kept pulled up, regardless of the dropping out of relay 171'. Furthermore, in lieu of the single contact 185, four contacts 184' are here provided in order that the four busses 69 may be kept separate back to the contacts 180', 181', 182' and 183' respectively. Thereby, although the impulse counter of Fig. 5 imparts the same impulses to all four of the wires 69, these wires

will not be short circuited together after relay 176' releases.

It will be noted that each of the rotary switches in both of the above described impulse counters 5 may be of the type as schematically indicated, which have interconnected duplicate sets of contacts and duplicate wiper arms, so that successive operations of the switch may be had without necessitating a complete revolution thereof. It 10 will be understood that other arrangements of various known types might be provided for locally counting the necessary impulses.

Operation of wipe-out connections.—If it is desired to operate the "wipe-out" relay 37, the impulse storage relays 27 are operated so as to apply a battery to one of the connection wires 28 designated as 202. The "wipe-out" relay 37 will thereupon be energized and its four contacts 15 will be closed for applying current from a battery indicated at 204 to all four of the wires 28 running to the "open," "high," "low" and "last" relays 29 to 32. Therefore the "open," "high," "low" and "last" indicators for the particular stock to be chosen will all be placed in operative condition. Relay 37 also has a "make" and "break" contact at 205, the "break" contact of which is interposed in the circuit of wire 10 by way of a return wire 10'. Thus, when relay 37 is not energized, wires 10 and 10' will provide a continuous path from "GO" of impulse counter 67 to "GI" of impulse counter 57. However, when relay 37 is energized, and its lower contact spring moves to its "make" position, wire 10' will be disconnected from wire 10 and instead will be connected to the coil of a relay 206, thence to battery and ground 207. Relay 206 thereupon opens its contacts at 208 and thus breaks the circuit of release bus 136, causing release relay 133 to drop out. The "wipe-out" relay thus not only disconnects impulse counter 57 and prevents its operation, but also opens the release bus to restore the selector circuits to normal. Also if desired, the "wipe-out" relay may be utilized to operate the relay 24 to shift the next selecting impulses to the other portion of the system. This may be accomplished by connection wire 68' running from wire 68 (see Fig. 1b) to a "make" contact 205' under the control of relay 37, thence the wire 68' runs to wire 142 (see Fig. 1a). Therefore when connection 68 becomes grounded and the "wipe-out" relay 37 is also energized, a ground connection will be applied to wire 142 resulting in the actuation of relay 24, which thereupon operates its associated circuits in the same manner as above described.

It will be understood that the relays 34, 35 and 36 operate to perform their above described functions by reason of the control of their contacts in a manner similar to the control of contacts 203 by the relay 37.

Indicator circuit connections.—It will be noted that the terminals as at 208 of all of the indicators (see Fig. 1d) are connected to a "restoration" bus 209, which is grounded at 210 (see Fig. 1b). The indicator circuits are arranged so that the "restoration" impulses from the impulse counter 67 will all find a return ground over this "restoration" bus. At the completion of the restoration impulses, however, a relay 211 will be operated by reason of the grounding of the wire 10' (see Fig. 1b), a circuit running from 10', through relay 211 to battery and ground at 212. Relay 211 thereupon closes its contacts at 213 for connecting the ground 210 to "actuation" bus 214. This bus provides a ground return path for the "ac-

tuation" impulses supplied by the impulse counter 57.

In Fig. 1d as above stated, indicator connections are shown for the indicators for posting the quotations of one stock; the magnets for operating the indicator units are schematically indicated as at 215. Each indicator unit is provided with a cam operated switch or commutator as schematically indicated at 216, this commutator being arranged to normally connect the magnet winding through contacts or segments as at 217, to the "restoration" bus 209. However, when the indicator arrives at normal or "blank" position, the commutator or cam switches the magnet winding from contacts 217 to connect the same to contacts as at 218, whereby the return magnet circuits run to the "actuation" bus 214. Relatively quick detachable connections are schematically indicated as at 219 for the circuits of each of the indicators, whereby the indicators may be quickly removed or replaced in respect to the broker's board frame structure. It will be observed that a lead wire as at 220 from each indicator magnet is connected by way of connections as at 221 to contacts as at 222 respectively on the multicontact relay 85. When the relay 85 is energized, these connections are continued to terminals as at 223 which are arranged to be alternatively brought into engagement with either terminals 224 or 225, the latter terminals being associated respectively with the two sets of operating busses for the two parts of the system. It will be understood that the busses indicated are prolonged to provide for additional stock indicators of the same group. Also, the same busses may be branched as schematically indicated at 226 to extend to other adjacent groups of indicators.

Fig. 7 shows one type of indicator unit that may be used in connection with the system disclosed. In this figure the indicator drum is shown at 230 and is supported on the shaft 231 mounted in the indicator frame 232. Also secured on the shaft 231 is a ratchet wheel 233 which is operated by a fork 234 suitably pivoted in the frame, and having integrally formed thereon or connected thereto an armature 235 cooperating with the operating magnet 215 before referred to. As the magnet 215 is energized the pawl is rocked into the position shown in Fig. 7, and upon release is rocked clockwise by the spring 236. As stated before, each unit may be provided with slip connections which are indicated in Fig. 7 at 223', 209' and 214'. The slip connection 223' makes an electrical connection with the contacts 223, Fig. 1d, which through the contacts 224 or 225 may be connected to the busses 75 to 79 or 83 to 84. The slip connection 209' is adapted to be connected to the restoration ground 209 and the slip connection 214' is adapted to be connected to the actuation ground 214.

As shown in Fig. 7, impulses coming in over the slip connection 223' will pass over the winding magnet 215 and thence to the contact member 237 and from there to ground over the contact member 238 or 239 and the slip connections 209' and 214', respectively. The indicator is shown in Fig. 7 in the position into which it is moved by the last effective restoration impulse. In this position arm 240 on the indicator shaft 231 has opened the restoration circuit made through the contact members 237 and 238, and therefore has prevented any surplus impulses over the restoration circuit from operating the indicator beyond the normal position. The arm 240 at the same

time has moved the contact member 237 into contact with the member 239 thereby closing the actuating circuit through the magnet 215 to cause the indicators to be moved forward during setting-up operations.

If the terminals 223 are brought into engagement with the terminals 224, then the connected indicators for this particular stock will be operated from the selector apparatus shown in Fig. 1, whereas if the terminals 223 were brought into engagement with the terminals 225, then the duplicate selector apparatus would control the operation of these particular indicators. The plugs 50, etc. corresponding to the stocks now connected to the busses of the duplicate selector mechanism will be removed from the grid associated with the mechanism of Fig. 1 and then connected to the grid associated with the duplicate selector mechanism. In the transmission of the impulses from the central point, groups of impulses for operating indicators connected to terminals as at 224 are transmitted alternately with groups of impulses for stocks, the indicators for which are connected to terminals such as 225. As above stated, for more detailed description of the circuits shown in Fig. 1d, reference may be had to my copending application above mentioned relating to the indicator units and associated parts.

It may be noted that the system in its preferred example as disclosed, is intended to operate the duplicate selecting and indicating means alternately and it is unnecessary to operate successively the indicators of the same group or portion of the system. It may also be noted that it is unnecessary to apportion the listed stocks or items evenly between the two parts of the system. In fact with applicant's present commercial system now in use with the New York Stock Exchange quotations, the indicators are divided into two groups, the stocks represented by abbreviations of the first portion of the alphabet being in one group, the last portion of the alphabet being allotted to the other group. The allocation of indicators to these groups may vary from time to time, as for example when stocks represented by abbreviations of the first part of the alphabet are more active or where more numerous additions may be made to the listings represented by abbreviations of one or the other of the groups. To accommodate these varying conditions, applicant provides means whereby his multicontact relays 85 (see Fig. 1d) may have their terminals connected alternatively with the control busses of either portion of the system (through contact terminals 224 or through contact terminals 225). In this way the system may be so arranged that substantially the same number of quotations are actually transmitted during the day over the two duplicate portions of the system. Therefore the two portions of the system may conveniently be used alternately or if the system is divided into a greater number of portions than two, the plurality of sets of selecting and indicating apparatus may be used alternately, i. e., in rotation. Of course if the service is not quite evenly balanced between the two portions of the system, then a few "dummy" or "blank" quotations may be sent over one or the other of the portions of the system from time to time so that the alternate and prompt operation may still be maintained. That is, it will be apparent for example, that selecting impulses may be sent over one portion of the system to select indicator terminals to which no indi-

cator is connected, or any desired indicator or group of indicators might be reset to the previous quotation in order to preserve the alternate operation of the portions of the system.

It will be understood that while the above described apparatus is particularly adaptable for operating indicators such as disclosed in my said copending application, nevertheless other well known forms of indicator units might be satisfactorily substituted under various conditions.

The various relays such as of the local impulse generating devices and the releasing relays, etc., may be adjusted by trial to operate within such time limits as will most economically utilize the line wire or wires while at the same time assuring dependability of operation.

It will be understood that many features of the invention are applicable to transmitting arrangements other than the multiplex distributor as above described. For example, the circuits are adaptable for use in connection with analogous forms of multiplex radio transmitting circuits, or if desired, particularly for short distance work, the distributor may be replaced by direct line wires corresponding to the various distributor segments.

While the invention has been described in detail with respect to a certain preferred example thereof which gives satisfactory results, it will be understood by those skilled in the art, after understanding the invention, that various changes and modifications may be made without departing from the spirit and scope of the invention, and it is intended therefore, in the appended claims to cover all such changes and modifications.

What is claimed as new and is desired to be secured by Letters Patent is:

1. In a signalling system, a transmitting distributor operative in cycles, each cycle comprising the transmission of a complete message, a receiving distributor operative in corresponding cycles, means for operating said distributors in their respective cycles, a plurality of receiving mechanisms respectively operative by the cycles of operation of said distributors for posting a complete message, an electrical circuit connecting said distributors over which intelligence signals are transmitted, and means operated over said circuit to associate a certain cycle of said transmitting distributor with a selected cycle of the receiving distributor and thereby with a selected one of said receiving mechanisms.

2. In a telegraph system, a receiving distributor, a selecting mechanism, a plurality of receiving devices selectable thereby for subsequent operation in response to signals received by said distributor, and means associated with said distributor to cause said selecting mechanism to respond variously to select different ones of said receiving devices in response to the same code signals occurring in successive revolutions.

3. In combination, a multiplex telegraph system, a plurality of message display devices each associative with one of the channels of the system for displaying a message and each capable of variable operation, and means controllable over said system for operatively associating each of said display devices with one of the channels of said system with which it is at the time associated in accordance with a predetermined arrangement.

4. In a synchronous multiplex telegraph system, a plurality of receiving apparatuses each for receiving a message and each associative with one

of the channels of the multiplex system for receiving a message, transmitting apparatus adapted to be operated over a single channel of the multiplex system, and means operated over said channel to establish a predetermined phase relation between said transmitting and receiving apparatuses.

5. In combination, a multiplex telegraph system, a set of independent receiving devices each adapted to receive a message and respectively associated with individual channels of said system, a single transmitter including circuit connections for establishing signalling conditions with each of said channels, means to control all of said devices from said single transmitter, and means operated over a channel of the multiplex system to establish a predetermined phase relation between said single transmitter and said independent receiving devices.

20 6. Automatic broker's board apparatus comprising a plurality of indicators for posting various quotations such as "open," "high," "low," "last" and "yesterday's closing" of numerous stocks or other items, means for selectively operating the indicators for the "open," "high," "low," "last" and "yesterday's closing" of any desired stock, and means for concurrently restoring the "open," "high," "low" and "last" indicators of any desired stock.

25 7. Automatic broker's board apparatus comprising a plurality of indicators for posting quotations such as the "open," "high," "low" and "last" of numerous stocks or other items, means for operating the indicators for the "open," "high," "low" and "last" of any desired stock selectively singly or in unison.

30 8. In a receiving mechanism comprising a plurality of groups of indicators, a plurality of sets of storage devices for effectively storing impulses for subsequently controlling the selection and operation of any group of indicators, means responsive to the stored impulses in said storage devices for selecting and operating any group of indicators, and switch connections 40 whereby any group of indicators may be selected and operated from either of said sets of storage devices.

35 9. A stock quotation board comprising a plurality of indicators, means for receiving impulses to select and operate said indicators, a set of storage devices for storing received impulses corresponding to a complete quotation, a second set of storage devices for storing received impulses corresponding to a complete quotation, means for applying said received impulses alternately to said sets of storage devices, and means for selecting and operating said indicators from either set of storage devices.

40 10. The combination of a plurality of indicator assemblies, each assembly comprising a plurality of electromagnetically operated indicators, groups of storage relays, means controlled by said storage relay groups for selecting any one of said assemblies, impulsive means for transmitting impulses to the individual indicators of the selected assembly to restore the same, and a no reset group of storage relays for determining how many of the individual indicators of the selected assembly receive impulses from said impulsive means.

45 11. In a signaling system, a source of signals, a distributor having receiving segments corresponding to a plurality of groups of character code signals, two sets of storage elements associated with said distributor, means for applying

signals received on said receiving segments alternately to said sets of storage elements during successive cycles of operation of the distributor and retransmitting means associated with each set of storage elements.

12. In a signaling system, a source of signals, a distributor having receiving segments corresponding to a plurality of character code groups of signals, two sets of storage elements associated with said distributor, means for applying signals received on said receiving segments alternately to said sets of storage elements during successive cycles of operation of the distributor, and separate retransmitting means associated with each set of storage elements arranged to 15 retransmit said signals.

13. In a system of the character described, the combination of a receiving distributor, an indicator board comprising two sections, each of which includes a plurality of groups of indicators, means for selecting and operating any group of indicators on either of said boards, and means under the control of the distributor for controlling said selecting and operating means to select and operate the groups of indicators on 20 said boards alternately.

14. In a system of the character described, the combination of a receiving distributor, an indicator board having the stocks thereof divided into two groups, each of which stock groups includes a plurality of groups of indicators, means for selecting and operating any group of indicators in either of said stock groups, and means under the control of the distributor for controlling said selecting and operating means to select and operate the groups of indicators in said two stock groups alternately.

15. Automatic posting board apparatus comprising a plurality of indicators for posting the varying quotations of stocks or other items, means controlled from a distance for selecting for operation any desired indicators to be reset, local means for restoring the selected indicators after selection thereof, to a normal position, and means for receiving from a distance and effectively storing, during said restoration operation, groups of coded impulses representative of the new quotation or quotations to be posted by the chosen indicators and for rendering said coded impulses effective to operate the indicators after the same have been restored to normal settings.

16. Automatic posting board apparatus comprising a plurality of electromagnetic indicating devices each movable to exhibit a plurality of digits, a plurality of successively operable selecting devices for selecting indicators which it is desired to reset, means for controlling said selecting devices to cause the same to operate successively over a single group of impulse channels, several of said selecting devices including means for bringing said impulse channels into operating relationship with the succeeding selecting device, and means controlled by the last selecting device to be operated, for initiating the movement of the selected indicator or indicators.

17. Automatic posting board apparatus comprising a plurality of electromagnetic indicating devices each movable to exhibit a plurality of digits, a plurality of successively operable selecting devices for selecting indicators which it is desired to reset, said selecting devices being controllable successively over a single group of impulse channels, several of said selecting devices including means for bringing said impulse channels into operating relationship with the

succeeding selecting device, and means controlled by the last selecting device to be operated, for causing automatic restoration to normal of the indicator or indicators selected.

5 18. Automatic posting board apparatus comprising a plurality of indicating devices controllable by a distant transmitter over a small number of impulse channels, a plurality of selecting devices for choosing any indicators desired to be 10 reset, connections for associating said impulse channels successively with said selecting devices, connections controllable by the last selecting devices to be operated, for causing the selected indicator or indicators to be restored to a normal setting, and circuits completed upon such restoration for resetting the restored indicators to post a desired new quotation under the control of impulses received over said impulse channels.

20 19. Means for selectively controlling a large number of electromagnetic devices comprising multi-stage remotely controlled selecting means for choosing as between a plurality of connections, at least three groups of said connections 25 being provided, each of said groups corresponding to one selecting stage, a plurality of relays having normally open contacts, each of the connections of one of said groups being associated with one or more of said electromagnetic devices 30 through said normally open relay contacts, each of said connections of the others of said groups being associated with windings of one or more of said relays controlling said relay contacts, whereby the selection and energization of one 35 of the connections of the first of said groups, together with one of said connections of the other groups, will result in the energization of the circuit of one of said electromagnetic devices, the circuit of such selected device being closed 40 by the operation of one of said relays.

20. Selecting apparatus comprising an arrangement of two groups of conductors, each conductor of each group being arranged to cooperate with any one of the conductors of the other group when energized to make a particular selection, one of said groups comprising a much larger plurality than the other, means for choosing and energizing one conductor of each of said groups, and electromagnetic means connected with the conductors of the larger plurality whereby the chosen conductor of the larger plurality electromagnetically controls a circuit including the chosen conductor of the smaller plurality.

55 21. Selecting apparatus comprising an arrangement of two groups of conductors, each conductor of each group being arranged to cooperate with any one of the conductors of the other group when energized to make a particular 60 selection, one of said groups comprising a larger plurality than the other, means for choosing and energizing one conductor of each of said groups, electromagnetic means connected with the conductors of the larger plurality whereby the chosen conductor of the larger plurality electromagnetically controls a circuit including the chosen conductor of the smaller plurality, a plurality of groups of indicating devices, control busses common to said groups, and means 65 operated by said last named circuit for connecting a plurality of said indicating devices to said control busses.

70 22. Selecting apparatus comprising a plurality of selecting switches, an arrangement of two groups of conductors, each conductor of each

group being arranged to cooperate with any one of the conductors of the other group when energized to make a particular selection, one of said switches being connected to select a conductor of one of said groups, said other group of conductors being divided into a plurality of sub-groups, a plurality of multicontact relays, each of said sub-groups being under the control of one of said multicontact relays, another of said switches being connected to select any one of said relays and to thereby prepare a circuit through a contact of the chosen relay to a selected conductor of the sub-group controlled by the chosen relay.

23. Selecting apparatus comprising an arrangement of two groups of conductors, each conductor of each group being arranged to cooperate with any one of the conductors of the other group when energized to make a particular selection, means for choosing and energizing any one conductor in each of said groups, electromagnetic means connected with the conductors of one of said groups whereby the chosen conductor of such group electromagnetically controls a circuit including the chosen conductor of the other group, a plurality of groups of indicating devices, control busses common to said groups, and means operated by said last named circuit for connecting a plurality of said indicating devices to said control busses.

24. In a stock quotation system of the character described, a receiver comprising a single receiving distributor, a stock quotation board comprising two sections, each section including a plurality of groups of electromagnetically operated indicators, means operable responsive to signals received over said distributor for selecting any group of indicators on either of said boards for operation, means associated with each board section and responsive to impulses received for storing signals corresponding to the price to be set up on the selected indicators, means for directing said impulses into the price storage means associated with the board section including the chosen indicators, and impulse controlling means associated with each of said price storage means for operating the selected indicators under control of said of the price storage means whereby the selected indicators on either board may be operated while selection and price information is stored for the selection and operation of indicators on the other board section.

25. In a stock quotation system of the character described, a receiver comprising a single receiving distributor, a stock quotation board having the stocks thereof divided into two groups, each such stock group comprising a plurality of groups of electromagnetically operated indicators, means operable responsive to signals received over said distributor for selecting any group of indicators in either of said stock groups for operation, means associated with each stock group and responsive to impulses received for

storing signals corresponding to the price to be set up on the selected indicators, means for directing said impulses into the price storage means associated with the stock group including the chosen indicators, and impulse controlling means associated with each of said price storage means for operating the selected indicators under control of said of the price storage means whereby the selected indicators in either stock group may be operated while selection and price information is stored for the selection and operation of indicators in the other stock group.

26. In a receiving system for the reception of code signal messages divided into groups for communication over separate channels, each message being divided into item selection and item price portions, a telegraph circuit over which said messages are received; a storage device operatively associated with said telegraph circuit for storing the signals of one portion of each message, and a storage device operatively associated with said telegraph circuit for storing the signals relating to the other portion thereof; an item board having a plurality of indicators for each item, each indicator adapted to be stepped to indicating position by electrical impulses; means for selecting certain indicators of one item by signals stored in one storage device; a plurality of translating units, one for each channel, each unit adapted to transmit impulses to the selected indicators in accordance with the item price portion of the message; means for selecting the translating unit of the channel to which the item being quoted is assigned; and means operated by said translating unit for pulsing the selected indicators to selected new positions in accordance with the received code signals.

27. In a receiving system for the reception of quotation code signals for selecting an item and the price thereof, said items being divided into groups for transmission over separate channels, a telegraph circuit over which said signals are received; a storage device operatively associated with said telegraph circuit for storing the signals relating to the item selection, and a storage device operatively associated with said telegraph circuit for storing the signals relating to the price; an item board having a plurality of indicators for each item, each indicator adapted to be stepped to indicating position by electrical impulses; means for selecting certain indicators of one item by signals stored in one of said storage devices; a plurality of translating units, one for each channel, each unit adapted to transmit impulses to the selected indicators in accordance with the price signals received; means for selecting the translating unit of the channel to which the item being quoted is assigned; and means operated by said translating unit for pulsing the selected indicators to blank positions and thereafter pulsing them to selected new positions in accordance with the received code signals.
